R. RAINALTER

BOX FASTENER

Filed April 13, 1921

Fig. 1.

INVENTOR
Rudolph Reinatter
BY Anthony Brown
ATTORNEY

UNITED STATES PATENT OFFICE.

RUDOLPH RAINALTER, OF KANSAS CITY, MISSOURI.

BOX FASTENER.

Application filed April 13, 1921. Serial No. 461,126.

To all whom it may concern:

Be it known that I, RUDOLPH RAINALTER, a citizen of the United States, residing at Kansas City, in the county of Jackson and

5 State of Missouri, have invented certain new and useful Improvements in Box Fasteners; and I do declare the following to be a full, clear, and exact description of the invention, such as will enable others skilled in the art 10 to which it appertains to make and use the same, reference being had to the accompanying drawings and to the figures of reference marked thereon, which form a part of this specification.

15 My invention relates to box fasteners and consists in certain novel parts and combinations of parts, all of which will be specifically described hereinafter, it being understood that changes in form, proportion 20 and minor details of construction may be resorted to without departing from the spirit of the invention or sacrificing any of its advantages.

In the drawings,

25 Fig. 1 is a perspective view of a case equipped with a fastener constructed in accordance with my invention, parts being broken away to show the interior thereof.

Fig. 2 is a sectional view through the 30 lock.

Fig. 3 is a sectional view through one of the hinges.

Fig. 4 is a perspective view of one of the 35 hinges, and

Fig. 5 is a sectional view through a corner of the case showing the tie rod, fastening means and the corner brace.

The case is shown as comprising a bottom 1, ends 2 and 3, back 4 and a front wall 40 5. The end walls 2 and 3 are provided with grooves 6 and 7, in which may be located the flanges 8 of Z-shaped braces 9, the flanges 10 disposed opposite to the flanges 8 being adapted to overlap the shouldered portion 45 11 of the front and rear walls of the case so that an efficient metallic bracing means will be provided at the four corners of the case.

The bottom will be secured in any well 50 known manner. The sides and ends are tied together by tie rods 12 and 13, which intersect one another, the rods being provided with threaded ends 14 for the cross rods and threaded ends 15 for the longitudinal rods 13. The ends of the longitudinal rods engage threaded nipples or sleeves 16 in one

end of the case, the opposite end of the rod being provided with a head. The nipples or sleeves may be screwed onto the ends of the rods 13, as shown in Fig. 5.

Similar sleeves 19 may be provided in the front end of the box for the threaded ends 14 of the rod 12. Therefore, tension may be placed on the rods to efficiently tie the parts together, both longitudinally and transversely and if desired, a vertical partition 60 20 may be provided for the interior of the box, as shown in Fig. 1.

The case is provided with a lid or cover 21, adapted to be hingedly secured to the rear wall 4 of the case. The preferred form of 70 hinge is shown in Fig. 4 as comprising a substantially U-shaped wall engaging member 22 having a front wall 23 and a rear wall 24, connected by a web 25. The rear wall 24 is shown as cut so as to provide upstanding hinge members 26 and 27, terminating in barrels 28 and 29, between the ends of which is an aligning barrel 30 on the end of the strap 31, which is fastened to the cover 21 by the fastening device 32. The 75 barrels 28 and 29 and the barrel 30 are connected by a hinged pintle 33, as clearly seen in Fig. 4.

The U-shaped member 22 is mounted upon the rear edge of the wall member 4, the distance between the walls 23 and 24 being substantially the thickness of the wall 4 so that the member 22 can be slipped over the edge of the same, as shown in Fig. 3.

The lower end of the wall 23 terminates in a sleeve or barrel-shaped portion 34, which is engaged by a rod 35, fastened to the case in substantially the same manner as the rods 13; the rod 35, therefore, constituting a hinged securing means as well as a 90 tension or bracing member for the case.

When the parts or hinged members are in the positions shown in Figs. 3 and 4, it is apparent that the two hinged members 22 will constitute an efficient means for hing- 100 edly securing the cover 21 to the case.

At the forward edge of the cover 21 is a plate 36 having its end extending slightly beyond the forward edge of the cover 21 and provided with a seal-wire-receiving opening 37, adapted to align with the seal-wire-receiving opening 38 of a lock member which consists of a U-shaped member having a rear plate 39, a front plate 40 and a connecting web 41. The plates 105 110

39 and 40 lie against the opposite sides of the front wall or panel 5 of the box. There is a tongue 42 struck out from the wall 40 and bent up so as to lie parallel with the forwardly projecting end of the plate in which is located the opening 38, the tongue 42 lying parallel with the projecting end of the plate 36 when the parts are together, as shown in Fig. 2.

10 The lower edge of the wall 39 is bent back upon itself to form a barrel 43 to receive a tie rod 44, corresponding to the tie rod 35 so that the U-shaped latch member will be held in place. The U-shaped latch member carries a laterally projecting locking bolt 46, which extends through the plates 39 and 40 and is provided with a hook-shaped extension 47 at one end and a push knob 48 at the other end, there being a collar 49 adjacent to the plate 40. One end of a coil spring 50 bears against the collar and the other against the inner face of the plate 39. Therefore, the hook-shaped portion 47 may be moved out of engagement with the hook-shaped flange 51, formed by striking out a portion from the plate 36, as clearly seen in Figs. 1 and 2.

When the parts are in the position shown in Fig. 2 and it is desired to unlock the locking bolt 47 from the keeper or flange 51, the operator may press on the end 48, moving the locking bolt against the action of the spring 50 so that the hook-shaped end 47 will move out of engagement with the latch flange 51. Then if the seal 52 is broken, the top of the box or lid can be raised from the box or case proper, it being understood that the openings 37 and 38 are for seal wires which may be introduced therethrough with their ends sealed for the purpose of shipping, etc.

Hand engaging openings 53 and 54 may be provided in the ends of the box, if desired.

45 When the parts are assembled as shown it will be apparent that the ends will be efficiently braced, that the tie rods 12 and 13 will hold the parts together, that the hinges may be easily applied to the box and that 50 an efficient lock or fastening means may be

provided, adapted to be readily unlatched if desired.

From the drawings it will be observed that the members 9 extend from the top to the bottom of the box and, together with 55 the sides 4 and 5, prevent the bottom from sliding laterally, the longitudinal movement of the bottom 1 being prevented by the end members 2 and 3.

There is a special advantage in providing 60 the locking means on the front of the box with the seal portions 37 and 38 projecting outwardly. With such a construction, the boxes can be filled and piled one upon the 65 other, then the sealer can have access to the projections so that the seals can be put on the boxes while they are in piles or tiers.

This is a material advantage over those 70 forms of locks which have the seals on the top, as will be clearly apparent.

It will also be apparent that the entire 75 case may be cut and assembled without the necessity of employing nails and that the finished product will be quite strong and durable.

What I claim and desire to secure by Letters-Patent is:

1. A box fastener comprising a bolt, supporting means to fit over the edge of a box, 80 said means having a stay wire engaging loop, a spring-pressed bolt extending transversely through said means and having a hooked end, and a complementary plate for attachment to the lid of the box and having a lip for engagement with the bolt.

2. A box fastener consisting of a plate bent in inverted U form and having a stay 85 rod engaging loop, an outstanding lip struck from the plate and having an opening through which a seal wire may be threaded, a spring-pressed bolt extending through the U-shaped plate and having a hooked end, and a complementary plate having a lip to be engaged by the hook on the bolt and an end provided with an opening to align with the opening in the outstanding lip of the plate.

In testimony whereof I affix my signature.

RUDOLPH RAINALTER.
